United States Patent Office

Des. 228,273
Patented Sept. 4, 1973

228,273

CUP

Niels Refsgaard, Ishøj Per Taastrup, Denmark, assignor
to Dansk Designs Ltd., Mount Kisco, N.Y.

Filed Sept. 29, 1971, Ser. No. 184,971

Term of patent 14 years

Int. Cl. D7—01

U.S. Cl. D7—9

FIG. 1

FIG. 2

FIG. 3

FIG. 1 is a top plan view of a cup showing my novel
design;

FIG. 2 is a side elevational view thereof;

FIG. 3 is an end elevational view thereof.

The bottom of the cup is substantially plain.

I claim:

The ornamental design for a cup, as shown and
described.
